JOHN H. IRWIN, OF CHICAGO, ILLINOIS.

Letters Patent No. 86,549, dated February 2, 1869

IMPROVEMENT IN LANTERNS.

The Schedule referred to in these Letters Patent and making part of the same.

To all whom it may concern:

Be it known that I, JOHN H. IRWIN, of Chicago, in the county of Cook, and State of Illinois, have invented a new and useful Improvement in Lanterns; and I do hereby declare and make known that the following is a full, clear, and exact description of the same, reference being had to the accompanying drawings, and the letters and figures marked thereon, which form part of this specification.

My said invention relates to lanterns having tubes extending from a funnel-shaped top to the base of the lantern, whereby the heat of the flame of the lamp, rising into said funnel-shaped top, produces a current of air down through said tubes, so as to supply the burner with oxygen to support the flame; and

It consists in a novel arrangement in the said funnel to gather the air, to cause it to enter said tubes, for the purpose above mentioned; and

It also consists in a novel arrangement, whereby the top of the lantern, which holds the upper end of the globe, can be moved or adjusted up and down, to permit the said globe to be removed and replaced, when desired, as hereinafter more fully set forth.

To enable those skilled in the art to understand how to construct and use my said invention, I will proceed to describe the same with particularity, making reference, in so doing, to the aforesaid drawings, in which—

Figure 1 is a central vertical section of my improvement;

Figure 2 is a side view thereof; and

Figure 3 is a bottom view of the funnel aforesaid, with its attachments.

Similar letters of reference in the several figures denote the same parts of my invention.

A represents the oil-pot of the lantern, which is surrounded by an air-chamber, B, into which the tubes C C open, as shown.

Resting in any suitable manner upon the burner or base of the lantern, is a perforated circular plate, H, having a vertical rim, which receives and supports the lower end of the globe G, as shown.

The upper end of the globe fits closely, but movably, in a ring, F, which ring is attached to an inverted funnel-shaped cap, E, by means of arms, a, leaving a suitable space between said ring F and the ball or funnel E, as shown.

The said inverted funnel E is provided with a collar, fitting upon a vertical tube, D, which tube branches out and forms the aforesaid tubes C C, as shown.

Surrounding said tube D, resting upon the collar of E, and against the shoulders formed by the tubes C,

is a spring, S, which serves to press down the funnel E, and thus holds the ring F close down upon and over the top of the globe, to hold the globe securely in place.

At the same time, when it is desired to remove the globe, the said spring will yield, to permit the ring F to be raised up from the globe for that purpose.

The aforesaid tube D projects through the funnel-plate E, and is provided with an inner or second funnel or flange, b, which serves the same purpose, to a certain extent, as the outer flange E, and also prevents the funnel-plate or flange E from being forced off from the tube by the spring S.

The heat of the burner, rising, creates a current of air, through the tubes C, into the burner, while fresh air is admitted through the perforated plate H, which rises near the glass, forming a shell of cold air next to the glass, and preventing the heating of the same, and of the metallic top, and, at the same time, mingling with the descending current in the tubes C C, to supply the flame.

One feature in a lantern of this construction is that it is a self-regulator, and if the wick should be turned up too high to cause the same to smoke, the effect of such condition upon the air-currents supplying the flame with oxygen is to subdue and reduce the combustion, so that it shall not smoke.

The flanges E b, provided they be arranged above the flange or ring F, so as to leave a horizontal unobstructed passage between them and the said ring F, or the top of the globe, cause the wind, blowing laterally against the lantern, to pass upward into the tube D, assisting the aforesaid currents in the tubes C C, instead of blowing downward into the globe, which would be the case if said flanges E b, or one or more of them, were not used, or were arranged within and below the top of the globe.

Having described the construction and operation of my invention, I will specify what I claim, and desire to secure by Letters Patent.

1. I claim the arrangement, beneath the funnel-plate E, of the prolonged tube D, and one or more flanges b, arranged substantially as and for the purposes set forth.

2. I claim, in combination with the ring F, funnel-plate E, and tube D, a spring, S, arranged to operate in the manner and for the purposes specified.

J. H. IRWIN.
